CLAIM

The ornamental design for a telephone base, substantially as shown and described.

DESCRIPTION

FIG. 1 is a front and side perspective view from above of a telephone base showing our new design;

FIG. 2 is a top plan view;

FIG. 3 is a right side elevational view thereof, the left side being identical; and

FIG. 4 is an end elevational view, the opposite end being substantially identical.

FIG. 1

FIG. 2

FIG. 3

FIG. 4
